UNITED STATES PATENT OFFICE.

WILLIAM F. HOFMANN, OF BROOKLYN, NEW YORK, ASSIGNOR TO H. L. JUDD CO., OF NEW YORK, N. Y., A CORPORATION OF DELAWARE.

DESIGN FOR A CURTAIN-POLE CENTER ORNAMENT.

Application filed May 13, 1926. Serial No. 17,677. Term of patent 3½ years.

To all whom it may concern:

Be it known that I, WILLIAM F. HOFMANN, a citizen of the United States of America, and a resident of the city of New York, borough of Brooklyn, in the county of Kings and State of New York, United States of America, have invented a new, original, and ornamental Design for a Curtain-Pole Center Ornament, of which the following is a specification, reference being

had to the accompanying drawing, forming part thereof.

The figure is a perspective view of a curtain pole center ornament embodying my new design.

I claim:

The ornamental design for a curtain pole center ornament, as shown.

WILLIAM F. HOFMANN.
